UNITED STATES PATENT OFFICE.

BRUCE E. EATON, OF DALLAS, TEXAS.

FAUCET-DRAIN.

1,324,110.

Specification of Letters Patent.

Patented Dec. 9, 1919.

Application filed April 15, 1919. Serial No. 290,136.

To all whom it may concern:

Be it known that I, BRUCE E. EATON, a citizen of the United States, residing at Dallas, in the county of Dallas and State of Texas, have invented new and useful Improvements in Faucet-Drains, of which the following is a specification.

This invention relates to drain attachments for faucets or similar water dispensing devices, the object being to provide means for automatically admitting air into the pipe after the water supply has been cut off and to drain the pipes without opening the faucet, thereby eliminating the danger of freezing and damaging the pipes.

Another object is the provision of a device of this character in which the vent will be automatically closed by pressure of the water when the supply is again restored, so that leakage of the faucet is prevented.

A further object is to provide a drain which may be used in connection with the ordinary pipes or faucets now in use, the application of the invention requiring only a slight addition and no material change in construction, so that only a slight increase in the cost of manufacture results.

With the above and other objects in view, the invention consists in the following novel features and details of construction to be hereinafter more fully described, and illustrated in the accompanying drawings.

In the drawings:

Figure 1 is a longitudinal sectional view of a faucet showing the valve in side elevation, with the invention applied thereto.

Fig. 2 is an enlarged fragmentary sectional view taken through the lower end of the valve stem the float being shown in elevation.

Fig. 3 is an enlarged detail perspective view of the float.

Referring in detail to the drawings, in which like characters of reference denote corresponding parts, the faucet is indicated at 10 and includes a valve seat 11, which is adapted to be closed by a valve 12 carried by a rotary stem 13. All of the foregoing described features are included in a faucet of the ordinary type, the invention residing in the application of an automatically operated vent which will now be described.

Formed in the bottom of the stem 13 and extending longitudinally thereof is a passage 14, the said passage extending for an appreciable distance in the length of the

valve stem and having its inner end in communication with a transversely disposed opening 15, which in the present form of invention extends diametrically through the stem. The lower or inlet end of the passage 14 is in communication with that portion of the faucet through which water flows from the pipes, so that when this end of the passage is open, water may flow through the 65 said passage and through the opening 15, which is in communication with the outlet end 16 of the faucet.

The passage through the valve stem is adapted to be automatically closed and to 70 remain in such closed position under the pressure of water passing through the faucet through the medium of a float 17, this float acting to cover and close the inlet or lower end of the passage. Carried by the float 75 17 and extending into the passage is a stem 19, which terminates in a hook 20, the latter being adapted to receive a pin 21 which passes through the transverse opening 15 and by this means will connect the float to the valve 80 stem. The length of the stem 19 is such as to permit of a limited play of the float in a direction longitudinal of the stem 13. To properly seat the float and to guide the same in its longitudinal movement, there is provided a plurality of pins 22 which also extend within the passage 14 and are guided by the wall of the passage. It is, of course, 85 understood that the connecting means just described may be varied as desired and it is 90 not the purpose of the present application to limit the invention to the particular means shown and described.

In the ordinary use of the faucet, the float 17 is held in position to close the passage 14 95 by the pressure of the water against the said float, but when the water supply is cut off and pressure relieved the float will leave its seat and open the passage and admit air to the pipe and drain the latter without the 100 necessity of opening the faucet. By this means the freezing of the water which would otherwise be left in the pipe is prevented.

The invention is susceptible of various changes in the form, proportions and minor 105 details of construction and the right is herein reserved to make such changes as properly fall within the scope of the appended claims.

Having thus described the invention, what is claimed as new, is:—

1. The combination with a faucet having a longitudinally disposed passage in the in-

ner end of the valve stem and a transverse opening connected therewith, of a float adapted to close the inlet end of said passage and a hook carried by the float extending within said passage for engagement with means carried by the valve stem for permitting a limited movement of the float in a longitudinal direction with respect to the stem.

- 10 2. The combination with a faucet having a longitudinally disposed passage in the inner end of the valve stem and a transverse opening connected therewith, of a float connected to said valve stem and adapted to close the inlet end of said passage, guide means carried by the float and extending within the passage and a pin extending through the transverse opening for connect-
- 15

ing the float and stem and permitting a limited independent movement of the float. 20

3. The combination with a faucet having a rotatable valve and a longitudinally disposed passage in the inner end of the valve stem and a transverse opening connected thereto, of a float connected to said valve 25 stem and adapted to close the inlet end of the passage under pressure of liquid within the faucet, means connecting the float and valve stem for permitting a limited longitudinal movement of the float with respect 30 to the stem and spaced parallel pins projecting from the float into the stem for guiding the former in its movement.

In testimony whereof I affix my signature.

BRUCE E. EATON.
